METHOD OF MINING AND APPARATUS
THEREFOR

Walter B. Lang, Washington, D. C.

Application February 6, 1948, Serial No. 6,685

19 Claims. (Cl. 262—1)

1

This invention relates to mining and aims to provide an improved method and means for increasing the useful yield of mines and preserving the geological structure of the overburden.

In particular the invention has for objects, severally and inter-dependently:

1. The provision of an improved method of making useful disposition of mine wastes in such a way as to enable removal of the standing ore columns left in the conventional room and pillar mining method, thus increasing the yield of the mine without danger of subsidence or need of timbering;

2. The provision of an improved method of erecting and consolidating mine wastes, and particularly crystallizable mine wastes, to form consolidated columns extending between and integralized with the hanging and foot walls of the mine opening;

3. The provision of a method which enables the simultaneous production in the so erected columns of indicating openings by which any tendency toward failure thereof may be detected before any serious failure occurs;

4. The provision of an improved method of erecting sectional forms to effect a tight seal thereof to the hanging and foot walls of the mine opening to provide for the formation therein of such integralized consolidated columns;

5. The provision of a method and means particularly adapted for economic erection of consolidated detritus columns in the cleared areas of mine galleries and the like, enabling subsequent removal of the ore body columns therebetween;

6. The provision of a method and means particularly adapted for potash mines and the like for establishing therein consolidated columns of detritus or gangue such as common salt adequate to support the overburden and enable removal of the entire economic bed or body of ore;

7. An improved method and means for cutting or generating in the hanging, foot or other walls of mine galleries ring-like seats for the reception of standardized chambering forms;

8. The provision of an improved chambering method and chambering forms for the erection of consolidated columns therein; and

9. The provision of improved seat generating equipment and improved sectional forms co-operable for easy transportation to, erection at and removal from place to place in the mine.

Other objects and advantages of the invention will be apparent from the following description of preferred embodiments of methods and means exemplifying the same.

With such objects in view the invention consists in the details of arrangement and combina-

2

tions of parts and in the novel steps and combinations thereof hereinafter described and claimed.

In the accompanying drawings illustrating a preferred embodiment of the invention,

Fig. 1 is a diagrammatic sectional plan through a region of mine galleries,

Fig. 2 is a diagrammatic vertical section taken on the line 2—2 of Fig. 1,

10 Fig. 3 is a similar view after erection of columns and removal of ore bodies from between the same by the method of this invention.

15 Fig. 4 is a more or less diagrammatic side elevation of a channeling device in accordance with the invention,

Fig. 5 is a diagrammatic detail of the pump arrangement taken on the line 5—5 of Fig. 4 looking in the direction of the arrows,

20 Fig. 6 is a diagrammatic sectional detail through one of the cutter feed control valves,

Fig. 7 is a vertical section illustrating one embodiment of column form for practicing the invention,

25 Fig. 8 shows in diagrammatic form one embodiment of liquid pressure pulsator and supply connected to the casting form.

In mining operations, and particularly in the case of potash mines and the like in which the deposits occur in overlapping lenticular form, the conventional mining method involves steps generally as follows:

Initially a shaft is sunk through a number of overlapping lenses and beds. A gallery is then opened in the lens appearing to contain the richest ore. This lens frequently is one of the lower lenses penetrated by the shaft. In such case the upper lenses of less rich ore are usually bypassed and reserved for working only after economic working-out of the richest lens. As the mine

30 gallery progresses in the selected lens or ore body, to prevent subsidence of overlying structures, some twenty-five per cent or more of the ore is left in place in standing columns 10 as shown in Figs. 1 and 2. Failure to leave adequate standing

35 walls or columns is apt to result in subsidence of the hanging wall 12, loss and delay in working the selected lens, and damage or rupture of overlying beds rendering them difficult to work. Also failure to have adequate walls 10 in underlying

40 beds which have been worked out, is apt to cause subsidence during working of overlying structures with danger to the personnel and equipment there employed, and prevents use of the excavated working for storage and other purposes currently

45 advocated by some authorities.

50 Efforts have been made in some localities where timber is available, to reduce the amount of ore necessary to be left in pillar form; but timbering

55 exemplifying the same.

is expensive, involves risk of fire and rotting, is merely a temporary expedient, and is frequently not economically feasible. Furthermore when the cost of timbering is added to other production costs, the total cost per yard of the mining operation is increased, and it becomes uneconomic to work ore bodies which otherwise would be sufficiently rich to justify the mining thereof.

Most ore bodies contain warts or horses of lean ore or ore high in gangue which must be removed in mine tunneling in pursuit of the richer bodies of ore. The disposal of a large amount of gangue is not only troublesome but expensive and the more of it that can be made use of in the mine, the lower the cost of operation. For example in potash mines the potash occurs in intimate association with common salt or halite and the volume of halite to be separated from the sylvite is large. It cannot be disposed of in rivers, and where stacked in open piles becomes an ever increasing nuisance.

My invention, however, enables useful disposition of such mine wastes, particularly of crystallizable mine wastes such as halite and the like, while at the same time enabling the standing ore pillars to be removed, thus increasing the yield of the mine without introducing danger of subsidence, and eliminating the need for timber. To this end, as shown in Figs. 1 and 3, I erect between the ore pillars 10 left by the conventional room and pillar method, consolidating columns 11 consisting predominantly or entirely of mine wastes, and sufficient in area to afford complete support for the overburden, and thereafter remove the ore pillars 10 from between the so erected columns 11.

In the preferred practice of this method which is particularly but not exclusively applicable to potash mines and the like yielding mine wastes including crystallizable material, I find that such columns may be best erected by erecting, between the ore pillars 10, casting forms embracing spaces extending from the hanging wall 12 to the foot wall 13 of the opening and sealed thereto, substantially filling said forms with such mine wastes in solid and liquid form, pulsating the material to eliminate voids therein, and allowing the contents of the forms to consolidate by crystallization, preferably while maintaining it under pressure, to form solid columns integralized with the hanging and foot walls, the structure of which is substantially as strong as that of the original ore body.

In order to effect the sealing of the casting forms notwithstanding irregularities in the hanging or foot walls, or both, of the mine gallery, my method contemplates the generation in the mine walls of ring-like seats 13 (Figs. 3, 4 and 7) for the reception of sealing rings 14 and 14a (Fig. 7) shown in the form of split rubber rings or gaskets or the like, against which the casting forms generally indicated at 15, Fig. 7, may be erected, such casting forms being provided with ingress means such as the manhole 16 and liquid inlet connection 17, for the introduction of solid and liquid wastes and the application of pulsating and fixed pressures thereto. These phases of the invention will now be described in order.

Channeling

As above noted the first step of this method comprises the formation of ring-like seats 13 in the walls of the mine between which the columns are to be erected. A preferred form of apparatus suitable for this purpose is shown in Fig. 4. In

the form there shown the apparatus comprises a fluid pressure, preferably a hydraulic pressure, jack post having at its ends bearing plates or feet 21 with an extensible hydraulic cylinder and piston 22 and 23 positionable therebetween and adapted to be extended or collapsed by hydraulic pressure application and release through the connection 24 under control of the valve 25.

In the form shown the cylinder portion 22 of the jack post is provided with a squared end 26 fitting into a flaring squared socket in the foot member 20 to prevent rotation thereof, and the piston 23 is provided with extension caps 27 to adapt it for various spacings of the mine walls, the last such cap 28 being coupled to the bearing plate 21 by a ball and socket connection 29.

In the form shown the cylinder 22 has mounted thereon a rotatable frame 30 supported between two sets of antifriction bearings 31 and 32, and thus adapted for rotation on the fixedly positioned cylinder. The cylinder 22 also carries a peripheral rack gear 23 and a slip-ring electrical connector 34 or the like hereinafter more fully described. The frame 30 in the form shown is adapted to detachably support a rotatable cutting frame, hereinafter described, so that these parts may be separated for transportation from place to place in the mine gallery. It will be observed that the separated jack post structures may be easily transported into and through the mine and may be quickly and firmly erected at any desired position in the mine opening at which a consolidated column 11 is to be erected.

In the form of Fig. 4 the rotatable cutting frame comprises a substantially rigid frame structure 40 formed at its inner end for detachable connection to the supporting frame 30 as by wing-nut or like securing means 41. At or near its outer end it is provided with rotatable cutter means 42 formed to channel the mine walls when the frame 40 is rotated.

Means is provided for feeding the cutters 42 as the depth of the channel 13 increases, this means in the form shown comprising hydraulic cylinders 43 coupled through suitable levers 44 and collars 45 to the tubular shafts 46 of the cutters 42, which are mounted for rotational and longitudinal movement in the journals 47 carried by the frame 40. Admission of measured quantities of hydraulic fluid under pressure to the cylinders 43 thus feeds the cutters 42 into the mine walls against the action of compression springs 48 surrounding tubular shafts 46, and release of fluid from the cylinders 43 allows the springs 48 to retract the cutters from the work. Such admission and release of fluid from the cylinders 43 may be controlled by suitable valves 50, Figs. 4 and 6, which may be ganged as shown for operation by a single hand lever 51. The fluid pressure supplied from the pumps 60 hereinafter described through conduits 52 is admitted to the cylinder connection 53 when the two-way valves 50 are turned to the position shown in solid lines in Fig. 6. When the valves are turned to the position shown in dotted lines in Fig. 6 the fluid from the cylinders 43 is vented through the vent line 54 to a suitable reservoir 55 carried by the frame 40.

The pumping means, Figs. 4 and 5, for supplying the measured volumes of liquid cylinders 43 preferably comprises two independent pumps 60 having plungers 61 spring-pressed against a pump cam 62. Each of the pumps 60 in the form shown comprises the usual inlet and outlet check valves 63 and 64 (Fig. 5) and preferably is provided with independent means 65 for adjust-

ing its volume of displacement, shown as a set screw projectable more or less into the pump chamber. The pumps 60 are mounted on a suitable support 66 which is adjustably carried as by the frame 40 (Fig. 5) so that the throw of the plungers may be simultaneously adjusted with respect to the cam 62. The pumps draw their fluid supply from the reservoir 55 (Fig. 4) and force measured quantities of hydraulic fluid to the cylinders 43 by way of the pressure liquid lines 52. As shown in Fig. 4 the cam 62 is rotated at a relatively low speed by a suitable drive, as the belt drive 67 connected through a speed reducer 68 to the driving motor 69.

As shown in Fig. 4 the driving motor 69 is directly coupled to drive gearing 70 suitably mounted on the frame 40 so as to rotate the cutter drive shaft 71 which in the form shown is splined to the tubular cutter shafts 46. These cutter shafts are preferably provided with extensible sections 72 to enable quick adjustment of the cutter spacing to the particular spacing of mine walls in which the channels 13 are to be cut.

From the gear reduction box 68 a further slow speed drive shaft 73 leads to gearing for rotating the cutter frame 40 relative to the support or jack post 22. In the form shown the slow speed drive shaft 73 connects to gearing 74 suitably mounted on the frame 40 which in turn drives a pinion 75 engaged with the peripheral rack gear 33 which is carried by the cylinder 22 as heretofore described.

The power leads 76 from driving motor 69 are coupled, as by plug-in connection 77, to the brushes 78 which are carried by the frame 30 and make contact with the slip-rings 34 as the frame is rotated relative thereto. Details of such slip-ring connections and equivalents thereof are well known to those skilled in the art and require no further description here. As is preferable when employing an electric drive, the slip-ring and brush assembly 34 and 78 may be enclosed in a housing (not shown) to isolate the open contacts from the surroundings. The slip-rings in the form shown are connected as by connector 79 to an electrical conduit 80 which passes to a point beyond the channel area 13 through a narrow trench 81 cut across such area to a suitable source of power indicated at 82.

With the foregoing construction it will be appreciated that after erection of the jack post 20-34, the cutter frame 40 and the parts carried thereby may be quickly attached to supporting frame 30. The cutters 42 may then be set by means of extensions 72 and pumps 60 to just clear the mine walls during rotation of frame 40. The trench 81 and electrical connections 77 and 79 may then be made, after which motor 69 may be put into operation, the valves 50 being positioned for admission of fluid to the cylinders 43. The cutter device will then operate automatically to cut the channels 13 until continuity of the seat 13 has been attained at which point the motor 69 may be deenergized and the cutters withdrawn by operation of the hand lever 51. The cutter frame may then be removed from the jack post and these parts may be transported to another location for the automatic cutting of another set of channels.

Casting of consolidated columns

After the channels 13 have been cut to an appropriate depth, the trench 81 is usually filled up to the level of the channel. In the preferred form shown in Fig. 7 the sectional casting forms

15 may be assembled to form a cylinder, say ten to twenty feet or more in diameter. They comprise a sealing ring 14, a base ring supportable thereon made up of sections 90, and further sections 91 and 92 assemblable in telescoping relation thereto. In the form of Fig. 7 the sections 92 are provided with flanged ends and support the sealing means 14a in the complementary one of the paired channels 13.

The base section in the form shown is provided with weep holes 93 connected to draw-off lines 94 controlled by valves 95. By these any excess liquid introduced into the assembled form may be readily withdrawn and progress of crystallization may be followed.

Suitable means is provided for holding the form sections 91 and 92 in assembled relation. As shown in Fig. 7 the sections 91 are held in engagement to form an annular ring by transverse tie-rods 96. These tie-rods are preferably of substantial diameter and tapered from one end toward the other. A diameter of from one and one-half to two inches is sufficient. Thus when the columns have consolidated in the assembled forms and the forms and tapered tie-rods are removed, the column is provided with transverse inspection openings 97 (Fig. 3). While the use of tapered rods 96 to afford such test holes is preferable throughout the column, other means for securing the form sections together may be used such as the contractable hoops 96a or bolts 96b for example. The test holes 97 (Fig. 3) may be inspected from time to time as the ore columns 10 (Figs. 1 and 2) are being removed, as well as thereafter, and if no distortion of the holes 97 appears will indicate that adequate support for the overburden has been provided and maintained.

Means is provided for forcing the forms 15 into sealing relation with the channels 13. In the form shown this means comprises wedge blocks 98 inserted between opposed flanges of the telescoping sections 91, 92 and fluid pressure expandable means in the form of collapsible hose sections 99 or the like interposable between opposed flanges of the telescoping sections, herein the flanges of the sections 90 and 91, and inflatable by fluid pressure supplied through a valved line or lines 100. Sealing gaskets of any conventional form are also preferably provided between the several form sections 14, 90, 91 and 92, so that on assembly and expansion the entire form becomes pressure tight.

When the forms have been erected so as to embrace a desired area of mine openings extending between hanging and foot walls thereof, as shown in Fig. 7, a mine waste mixture capable of being consolidated is introduced to the so-embraced space. Solid materials may be shoveled, conveyed, or blown in, as through manhole 16, and may be shoveled thereon or otherwise distributed within the space to substantially fill the same. The manhole cover 16 is then secured in place and consolidating material in liquid or slurry form is introduced through inlet connection 17 to completely fill the space within the casting form. The sludge or liquid introduced through pipe 17 in the case of potash mines and the like may

70 comprise refinery waste such as a strong brine or water suspension of salt crystals drawn from a suitable supply tank, as the tank 101 (Fig. 8). As the space embraced by the forms 15 is filled with such liquid material, the air therein may escape in any suitable way as through the valved

air eduction outlet 102 connected near the top of the enclosed space shown in Fig. 7.

When the voids in the enclosed space have been pumped substantially full of liquid material capable of consolidating the column, it is desirable that the contents of the forms be subjected to pulsations of pressure to eliminate any residual voids and cause intimate contact of the consolidating material with the solid wastes within the forms. As shown in Fig. 8 this may be effected by providing the sludge pump 103 with a check valved inlet 104, and providing its outlet with a weighted bypass valve, such as the spring biased bypass valve 105. Thus operation of the pump 103 when the chamber 15 has been substantially filled with liquid serves to reduce the pressure in the chamber 15, to which the pump is directly connected during the suction stroke of the pump, and to then raise the pressure therein to the value necessary to open the spring biased bypass 105.

When the forms have been filled, in the case of crystallizable material, until no more air is driven out through vent 102, the contents thereof are preferably maintained under pressure during the setting or crystallizing of the column. When the crystallization has progressed substantially to completion, which may be determined by the inability to draw any substantial quantity of liquid from the weep pipes 24, the forms and sealing rings may be removed and re-erected in another location. During the setting of the column, particularly if this is effected under pressure, the column becomes integralized with the foot and hanging walls of the mine opening. In the case of crystallizable material there is hardly any boundary between the column and the foot and hanging walls since crystal growth extends across such region. When the consolidated columns have set and are sufficient to support the overburden, the ore pillars 10, Figs. 1 and 2, may be removed.

Since the solid mine wastes may be obtained in part directly at the site of the work, and in part merely by returning them from the surface in the mine skips which otherwise would return empty, the supply of such materials to the site involve very little expense. Moreover where two skips are operating in counterbalanced relation the loading of the down-coming skip actually effects a saving in power consumption. The supply of liquid material to the inlet connection 17 may easily be effected by a simple pipe line extending from a surface tank 101 to the underground equipment. When so supplied the liquid head or a part thereof may be employed to fill the form 15 (Fig. 8) and maintain pressure thereon, and a cut-off 106 in such line may be closed to provide for pulsating operation of a pump such as the pump 103.

The invention is not limited to the particular details or order of steps or to the particular construction of apparatus described to illustrate the same, and various changes may be made therein without departing from the principles or sacrificing the advantages of the invention, which is defined in the following claims.

What I claim is:

1. In a room and pillar system of mining ore bodies and the like, the method of increasing the recovery of ore and obviating subsidence of overlying structures which consists in erecting, between the ore pillars left by the conventional room and pillar method, casting forms enclosing spaces

extending from the hanging wall to the foot wall of the mine opening, substantially filling said forms with mine wastes including settable material capable of penetrating into and bonding with the materials of the hanging and foot walls for consolidating the contents of said forms to form consolidated columns integralized with and extending between said hanging and foot walls, removing the casting forms after such consolidation has occurred, and thereafter removing the ore pillars from between the so erected columns.

2. In a room and pillar system for mining of potash beds and the like yielding crystallizable mine waste, the method of increasing the recovery of ore and obviating subsidence of overlying structures, which consists in erecting, between the ore pillars left by the conventional room and pillar method, casting forms embracing spaces extending from the hanging wall to the foot wall of the mine opening, substantially filling said forms with mine wastes including crystallizable material, introducing into said forms, to completely fill the same, crystallizable mine waste in finely broken and solution form, applying to the form-embraced body pulsations of pressure to eliminate voids therefrom and effect intimate contact of the solid and liquid portions of the material, maintaining liquid pressure on said material while allowing the material to consolidate by crystallization into a column integralized with the hanging and foot walls, removing the previously erected casting forms, and thereafter removing the ore pillars from between the so erected columns.

3. In a room and pillar system for mining of potash beds and the like using crystallizable mine waste, the method of increasing the recovery of ore and obviating subsidence of overlying structures, which consists in cutting ring-like seats in opposed walls of said galleries between the ore pillars left by the conventional room and pillar method, assembling casting forms in said seats to embrace casting spaces extending from the hanging wall to the foot wall of the mine opening, substantially filling said forms with mine waste including crystallizable material, introducing into said forms to completely fill the same crystallizable mine waste in finely broken and solution form, applying to the form-embraced body pulsations of pressure to eliminate voids therefrom and effect intimate contact of the solid and liquid portions of the material, maintaining liquid pressure on said material while allowing the material to consolidate by crystallization into a column integralized with the hanging and foot walls, removing the previously erected casting forms, and thereafter removing the ore pillars from between the so erected columns.

4. A method of the class described, which comprises cutting ring-like seats in opposed walls of a mine gallery, assembling sealing means in said seats with sectional forms juxtaposed thereto, jacking said forms into sealing relation to said sealing means, introducing into the space enclosed by said forms a filling consisting predominantly of mine waste, consolidating said filling into a column integralized with the hanging and foot walls of the gallery, and removing the casting forms and sealing means from about the so formed column.

5. A method of the class described, which comprises simultaneously cutting a pair of ring-like seats in opposed walls of a mine gallery, assembling sealing means in said seats with sectional forms juxtaposed thereto, jacking said forms into

sealing relation to said sealing means, introducing into the space enclosed by said forms a filling consisting predominantly of mine waste, consolidating said filling into a column integralized with the hanging and foot walls of the gallery, and removing the casting forms and sealing means from about the so formed column.

6. Apparatus for erecting columns in mine galleries comprising sealing means for forming packed seats on the walls of said galleries, sectional forms assemblable with said packed seats to enclose the space therebetween, means for retaining said forms in place, an access and filling door through at least one of said form sections, and a fluid inlet connection through at least one of said form sections.

7. Apparatus according to claim 6, said form retaining means comprising tapered rods extending through said enclosed space.

8. Apparatus according to claim 6 further comprising a liquid pressure pulsator and supply and conduits for attaching the same to said inlet connection.

9. Apparatus according to claim 8 further comprising means for withdrawing pulsation-free gases from said enclosed space.

10. Apparatus for erecting columns in mine galleries the hanging and foot walls of which are preformed with coaxial parallel ring seats therein, said apparatus comprising sealing rings receivable in said ring seats, sectional forms assemblable between said rings, and means for expanding said forms against said rings.

11. Apparatus according to claim 10, said sectional forms being assemblable in telescoping relation between said rings and said last named means including a fluid pressure expansible means interposed between said telescoping sections.

12. Apparatus according to claim 10, said sectional forms being assemblable in telescoping relation between said rings and said last named means including a wedging means interposed between said telescoping section.

13. Apparatus according to claim 10, said sectional forms comprising tapered members extending through the space embraced thereby.

14. Apparatus according to claim 10, said sectional forms comprising means for venting fluids from the top of the space embraced thereby.

15. Apparatus according to claim 10, said sectional forms being substantially fluid tight when erected, and said apparatus comprising a source of consolidating liquid under pressure and conduits for connecting the same with the space embraced by said forms.

16. Apparatus for erecting columns between the hanging and foot walls of mine galleries, said apparatus comprising a form having the shape of an annulus and laterally separable to enable its removal from a finished column and means for securing the form against such separation during the casting of a column therein, said form comprising a vertically expandable inflatable body having the shape of an annulus and laterally separable to enable its removal from the finished column and the inflation of which seals the form in place between reasonably smooth hanging and foot wall areas, said form having lateral ingress means for the introduction of column forming material to the interior thereof.

17. In a room and pillar system for mining of potash beds and the like using crystallizable mine waste, the method of increasing the re-

covery of ore and obviating subsidence of overlying structures, which consists in cutting ring-like seats in opposed walls of said galleries between the ore pillars left by the conventional room and pillar method, assembling casting forms in said seats to embrace casting spaces extending from the hanging wall to the foot wall of the mine opening, substantially filling said forms with mine waste including crystallizable material, introducing into said forms to completely fill the same crystallizable mine waste in finely broken and solution form, maintaining liquid pressure on said material while allowing the material to consolidate by crystallization into a column integralized with the hanging and foot walls, removing the casting forms from the integralized columns, and thereafter removing the ore pillars from between the so erected columns.

18. In a room and pillar system for mining of potash beds and the like using crystallizable mine waste, the method of increasing the recovery of ore and obviating subsidence of overlying structures, which consists in cutting ring-like seats in opposed walls of said galleries between the ore pillars left by the conventional room and pillar method, assembling casting forms in said seats to embrace casting spaces extending from the hanging wall to the foot wall of the mine opening, substantially filling said forms with mine waste including crystallizable material, introducing into said forms to completely fill the same crystallizable mine waste in finely broken and solution form, applying to the form-embraced body pulsations of pressure to eliminate voids therefrom and effect intimate contact of the solid and liquid portions of the material, allowing the material to consolidate by crystallization into a column integralized with the hanging and foot walls, removing the casting forms from the integralized columns, and thereafter removing the ore pillars from between the so erected columns.

19. In a room and pillar system for mining of potash beds and the like using crystallizable mine waste, the method of increasing the recovery of ore and obviating subsidence of overlying structures, which consists in cutting seats in opposed walls of said galleries between the ore pillars left by the conventional room and pillar method, assembling casting forms in said seats to enclose casting spaces extending from the hanging wall to the foot wall of the mine opening, filling said forms with mine waste including crystallizable mine waste in finely broken and solution form and allowing the same to consolidate by crystallization into columns integralized with the hanging and foot walls, removing the casting forms from the integralized columns, and thereafter removing the ore pillars from between the so erected columns.
